PROCESS OF BRIQUETING AND PRESSING FUELS.

1,052,093.

Specification of Letters Patent.

Patented Feb. 4, 1913.

Original application filed July 21, 1909, Serial No. 508,784. Divided and this application filed April 8, 1911. Serial No. 619,671.

To all whom it may concern:

Be it known that I, ÁRPÁD RÓNAY, a subject of the King of Hungary, and resident of Berlin, Germany, have invented certain new and useful Improvements in Processes of Briqueting and Pressing Fuels, of which the following is a specification.

This application is a division of my earlier application on which Patent No. 1,002,453 was issued September 5, 1911, in which are disclosed novel features applicable broadly to the making of briquets from loose material of various kinds, said briquets being adapted for use in a variety of ways. In the earlier application referred to, the claims have been directed particularly to the process based on said principles when applied to the briqueting of certain particular classes of waste material. The present application is directed to the use of similar principles when employed for the briqueting of air-dry non-briqueting fuel. In both the prior and the present application the processes require that all air be removed from the material to be briqueted simultaneously with the briqueting operation and a machine particularly adapted for applying both processes has been described and claimed in an application Serial No. 508,784, filed simultaneously with the prior application on which Patent No. 1,002,453 above referred to was granted.

That my invention may be better understood it may be stated that in making briquets and compressing small masses of material which are to be united to form an entirety, it is necessary to remove the air from the said material. It may be thought that the air can be removed in various ways. The employment of a momentary, very great pressure like a blow first suggested itself; air is not removed in this manner to the desired extent, however, since on the one hand the air has no time to escape during the momentary percussional action, whereas on the other hand the machine is very severely strained and unreasonable wear and tear produced. The same disadvantages are met with when the pressure, though not

brought about by blows, is caused very rapidly and when the maximum pressure obtained lasts a definite time. Another mode of removing the air consists in increasing the pressure continuously to a maximum, whereby, sliding molds being preferably used, opportunity is given to the air pressed to the sides to escape. In such a mode of operation air is removed in layers, the removal continuing gradually from the movable stamp to the stationary counter stamp. Now I have found that a continued rise of pressure, *i. e.* when the pressure rises by exactly equal amounts per unit of time or per each equal fraction of the time of the pressing operation, cannot insure a completely satisfactory briqueting. This observation resulted from perceiving that the amount of the increase in pressure per unit of time or per fraction of the time occupied by the pressing operation must be brought into relation with the admixture of air which is present in the stage of the pressing operation in question. The greater the percentage or admixture of air, the longer must the rise of pressure per unit of time or per fraction of the total time at disposal be brought about, whereas with diminishing admixture of air a rise of pressure all the greater may take place within the unit of time.

For carrying my invention into practice I employ instead of the continuous pressure used heretofore, one having several stages, preferably as many as possible; the greater the number of pressure stages, the closer the approximation to the ideal pressure curve. Increasing the number of pressure stages has the additional advantage that the operation of removing the air from the material being briqueted is facilitated owing to the consequent concussions. In the accompanying drawing a diagram shows in what manner such an approximation of the actual pressing operation to the ideal pressure curve is aimed at or obtained. The horizontal coördinates give the time in seconds whereas the vertical coördinates give the pressure in atmospheres. The ideal pressure

curve is represented by i , a maximum pressure of 2000 atmospheres brought about in 16 seconds being assumed. It is clear that at the end of the first quarter of the total 5 pressing period *i. e.* after four seconds, a pressure of about 120 kilos is employed; at the end of 8 seconds about 360 kilos; at the end of 12 seconds about 875 kilos; at the end of 14 seconds a pressure of about 1300 10 kilos; and at the end of 15 seconds a pressure of about 1575 kilos is obtained. If now the total pressure be subdivided into a number of pressure stages, *e. g.* into eight designated I to VIII, as is shown in the accompanying drawing, it is seen that the duration 15 of the pressure stages becomes constantly shorter with increasing pressure corresponding to the line of ideal pressure curve i ; thus the first pressure stage I lasts for about six 20 seconds, the second II only about three seconds, the third III about two seconds, and so on, the last pressure stage VIII lasting about one-half second. The diagram clearly shows that the smaller the number of pressure 25 stages, the less perfectly does the actual compression curve fit the pressure curve, whereas, on the other hand, with an increasing number of pressure stages the actual compression curve approximates more and 30 more closely to the ideal pressure curve. Furthermore it follows from the diagram that as the number of pressure stages increases, the concussions which occur when passing from one pressure stage to the next, 35 occupy a continually greater fraction of the total time, thereby producing an approximately continuous shaking movement favorable for removing the air. Whereas the ideal curve i gives those pressures which 40 are exerted by the operative face of the stamp, *i. e.* by the face of the briquet press on the material, j indicates the ideal curve of those pressures which are exerted upon 45 the hydraulic piston corresponding to the curve i ; a four-fold ratio of transmission is here assumed between the face of the hydraulic piston and the stamp of the press, a pressure of 2000 atmospheres at the latter corresponding to a pressure of 500 atmospheres 50 on the former so that at any given moment the ordinate of a point on the curve j is one-fourth the ordinate of the corresponding curve i . From this it follows that for obtaining the pressure stages such as 55 I, II, III, etc., in the cylinder of the press, the machine must be adjusted correspondingly to the pressure stages I', II', III', etc., which approach the curve i ; each of the pressure stages appertaining to the curve i 60 is four times greater in the example represented than the corresponding pressure stage which belongs to the curve j whereas the duration of these corresponding pressure

stages is equal. The number of pressure stages to be employed is dependent on the 65 percentage of air in the material, on the porosity, granularity, density and special physical properties of the material to be pressed, size and shape of the briquets to be made, and other considerations. According 70 to my invention I may employ it not only with materials such as coal, salt, sawdust, ore, fuels, refuse and peat, but I may also employ it for producing a rigid combination 75 of granular, powdery, leafy, fibrous or other substances of like form, sheets of paper, metal foil, etc., for example, for the purpose of alloying metals in the press cold by producing the state termed "cold-liquid." The application of the broad principles of 80 my invention is therefore not confined to briquetting processes, but may be applied also to all other compression operations, as for example forging, wire drawing and the like. 85

In my prior application, No. 508,784, referred to, I have particularly described the process of briquetting metal chips, shavings or other waste metals, such as iron filings, steel filings and the like and have called 90 attention to various modes of practising my invention and to various principles and applications thereof.

Other principles and modes of operation more particularly essential or desirable in 95 the briquetting of material other than fuels are not necessary to be described in this application, although belonging to the invention broadly.

My invention may be very advantageously 100 employed for making molded blocks of fuel or mixtures of fuel which in themselves are non-briquetting; the process is particularly adapted to the briquetting of slaty coal or lignite. In order to form these non-briquetting 105 materials into usable briquets, said material is first subjected to a total predetermined pressure according to the system of successive stages which have been above described; this material must be air-dry to 110 start with and free of any agglutinant. The block thus formed is then subjected to a sudden maximum pressure under the influence of which that air is removed from the mass which is inclosed in the individual particles 115 of the material and is driven out from the lowest layers of such particles by the bitumen which is emitted at this maximum pressure. There is to be found among fuels a large number of bodies containing practically 120 no bitumen or equivalent substance capable of becoming plastic under high pressure and hence acting as an agglutinant. If such material is to be briquetted, in order that not too high a pressure be required in 125 the second part of the pressing operation,

which would perhaps make the economy of the entire process doubtful, it is preferable to add to the material very small quantities of substances capable of becoming plastic or 5 agglutinative only at the high final pressure. Bituminous substances, such as bituminous slate, hard pitch, clay, clay-containing masses, lime, cement and the like are suitable for this purpose. In individual instances it 10 is preferable in the case of fuels to mix the binding substances with merely the outside surface of the finished briquet and to leave the core of the briquet unchanged so that the surface forms a crust containing the 15 binding substances. The agglutinant can be applied to the surface of the briquet in various ways, *e. g.* by coating the inside of the molds therewith. Briquets having their surfaces thus enriched with an agglutinant, *e. g.* 20 bitumen are then preferably exposed to the action of steam in order that the agglutinant may be forced by the same into the interior of the briquet.

The fuel briquets made according to my 25 invention, particularly coal briquets, may be coked on the surface. In many cases it will be found preferable to subsequently impregnate these coked briquets with bitumen in order to prevent moisture from penetrat- 30 ing into them.

Having described my invention I claim:

1. The herein described process of briquetting and pressing air-dry, non-briquetting fuel without the aid of an agglutinant 35 and completely removing the air therefrom, which consists in subjecting the fuel to a pressure which rises during a definite fraction of the duration of the pressure by an increasing amount per unit of time as the 40 percentage of air in the fuel decreases, whereby a block of fuel is obtained, and in thereupon subjecting the block to a sudden maximum pressure.

2. The herein described process of briquetting and pressing air-dry, non-briquetting fuel and completely removing the air therefrom, which consists in mixing with the fuel a very small quantity of a substance which only becomes agglutinative under the 50 action of a sudden, very high pressure, in subjecting the mixture thus obtained to a pressure which rises during a definite fraction of the duration of the pressure by an increasing amount per unit of time as the 55 percentage of air in the materials decreases, whereby a block of fuel is obtained, and in thereupon subjecting the block to a sudden maximum pressure.

3. The herein described process of briquetting air-dry, non-briquetting fuel and completely removing the air therefrom, which consists in bringing the fuel into the 60 form of a body and simultaneously applying

to the surface of the body a very small quantity of a substance, which only becomes ag- 65 glutinative under the action of a sudden, very high pressure, in subjecting the body to a pressure which rises during a definite fraction of the duration of the pressure by an increasing amount per unit of time as the 70 percentage of air in the fuel decreases, whereby a block of fuel is obtained, in there- upon subjecting the block to a sudden maxi- mum pressure.

4. The herein described process of bri- 75 queting air-dry, non-briquetting fuel and completely removing the air therefrom, which consists in coating the inside of a mold with a substance which only becomes agglutinative under the action of a sudden 80 very high pressure, in placing the fuel into the coated mold and thereby forming a body and applying to the surface thereof said sub- stance, in subjecting the body to a pressure which rises during a definite fraction of the 85 duration of the pressure by an increasing amount per unit of time as the percentage of air in the fuel decreases, whereby a block of fuel is obtained, in thereupon subjecting the block to a sudden maximum pressure. 90

5. The herein described process of bri- 95 queting air-dry, non-briquetting fuel and completely removing the air therefrom, which consists in coating the inside of a mold with a substance which only becomes agglutinative under the action of a sudden, very high pressure, in placing the fuel into the coated mold and thereby forming a body and applying to the surface thereof said sub- 100 stance, in subjecting the body to a pressure which rises during a definite fraction of the duration of the pressure by an increasing amount per unit of time as the percentage of air in the materials decreases, whereby a block of fuel is obtained, in there- 105 upon subjecting the block to a sudden maximum pressure, whereby a briquet having a crust is obtained, and in then subjecting the briquet to the action of steam.

6. The herein described process of bri- 110 queting and pressing air-dry, non-briquetting fuel without the aid of an agglutinant and completely removing the air therefrom, which consists in subjecting the fuel to a pressure which rises during a definite frac- 115 tion of the duration of the pressure by an increasing amount per unit of time as the percentage of air in the fuel decreases, whereby a block of fuel is obtained, and in thereupon subjecting the block to a sudden 120 maximum pressure, whereby a briquet is ob- tained, and in then coking the surface of the briquet.

7. The herein described process of bri- 125 queting and pressing air-dry, non-briquetting fuel without the aid of an agglutinant

and completely removing the air therefrom, which consists in subjecting the fuel to a pressure which rises during a definite fraction of the duration of the pressure by an increasing amount per unit of time as the percentage of air in the fuel decreases, whereby a block of fuel is obtained, and in thereupon subjecting the block to a sudden maximum pressure, whereby a briquet is obtained, and in then coking the surface of the

briquet, and subsequently impregnating the briquet with bitumen.

In testimony whereof I have hereunto set my hand in the presence of two subscribing witnesses.

ÁRPÁD RÓNAY.
